UNITED STATES PATENT OFFICE.

DANIEL W. TOWER, OF GRAND RAPIDS, MICHIGAN, ASSIGNOR TO GRAND RAPIDS BRASS CO., OF GRAND RAPIDS, MICHIGAN.

DEVICE FOR FASTENING FURNITURE-TRIMMINGS.

SPECIFICATION forming part of Letters Patent No. 745,404, dated December 1, 1903.

Application filed August 8, 1903. Serial No. 168,803. (No model.)

To all whom it may concern:

Be it known that I, DANIEL W. TOWER, a citizen of the United States, residing at Grand Rapids, in the county of Kent and State of Michigan, have invented a new and useful Device for Fastening Furniture-Trimmings, of which the following is a specification.

This invention relates to certain improvements in devices for securing handles, pulls, knobs, and similar trimmings to furniture and the like, and has for its principal object to provide a securing device that will securely hold a knob or other trimming in place, preventing turning or loosening of the knob or pull under all conditions of use.

A further object of the invention is to provide a securing device that will in part embed itself in the wood and prevent turning of the securing-screw, and, further, to apply the same construction to a knob or handle, so that neither the knob nor the screw can be turned and the knob held permanently in place.

A still further object of the invention is to provide a knob-securing device of simple and economic construction in which the securing member proper may be formed of steel, iron, or other cheap metal and concealed by an ornamental hood or washer of ornamental character.

With these and other objects in view the invention consists in the novel construction and arrangement of parts hereinafter described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a sectional elevation of a drawer-knob or the like provided with a fastening means in accordance with the invention. Fig. 2 is a detail perspective view of the knob. Fig. 3 is a similar view of the knob-locking washer and the ornamental washer that conceals it. Fig. 4 is a similar view of the headed portion of the screw and the screw-locking washer. Fig. 5 is a sectional view illustrating the application of the invention to an ordinary form of drawer-pull. Figs. 6 and 7 are views of

slightly modified constructions of washer. Figs. 8 and 9 are similar views of slight modifications of the screw-heads.

Similar numerals of reference are employed to indicate corresponding parts throughout the several figures of the drawings.

In drawer pulls and knobs of ordinary construction it is usual to employ a securing-screw extending through the front portion of the drawer from the rear surface toward the front and engaging a shank formed on the knob or pull, and in other cases to employ small eyebolts extending through the drawer-front and provided at their inner ends with ordinary nuts, the eyes receiving the ends of handles or pull members. Such fastenings are quickly loosened from constant use and are a source of annoyance in using the cheaper class of furniture.

In carrying out the present invention provision is made for firmly locking the parts, so that it will be impossible for the screw to become loosened or the knob to turn from ordinary use.

In the drawings, 1 represents the front of a drawer or similar structure provided with a transverse opening 2. Through this opening extends a securing-screw 3, the head 4 of the screw being disposed at the rear surface of the drawer-front. The base of the screw-head is flanged, as indicated at 5, and on its under surface are formed a number of projections or corrugations alternating with notches, as indicated at 7. The corrugations may be of any number and of any suitable shape, as shown in Figs. 4, 8, and 9. On the inner end of the screw is placed a washer 8, having inturned prongs or spurs 9 of any desired number which embed themselves in the woodwork when the screw is driven home, and the upper or outer face of said washer is provided with corrugations and notches, as indicated at 9', in order to engage the corresponding notches and corrugations on the inner face of the screw-head, and thus prevent the screw from turning. The screw enters the rearwardly-extended portion of a knob 10 or stud 11 of the drawer-pull, and in the latter case the stud is prevented from turning by the pull-handle 12, as shown in Fig. 5, so that it will be unnecessary to employ any auxiliary means for preventing turning

of the stud, and when once the screw is tightly turned the studs or prongs will embed themselves in the wood, while the interlocking of the notches and corrugations formed in the 5 adjacent faces of the screw and washer will prevent the screw from working loose.

When used in connection with a knob, it becomes necessary to provide some means for preventing turning of the knob under careless handling, and for this purpose the inner 10 end of the knob is provided with a boss 13, that is non-circular in form, and while in the present instance it is shown with two diametrically-opposed flattened sides 14 it is to be 15 understood that the shape may be triangular, rectangular, or any form that is not circular. This boss fits within an opening formed in a washer 15, the washer being dished and its peripheral flange having a plurality of 20 studs or prongs 16, that enter the wood at the front of the drawer. The receiving-opening for the boss is formed by a suitable die, and the side walls of the opening are turned inward to form flanges 17, preferably of a depth 25 about equal to that of the periphery flange 15, so that they may come into contact with the front of the drawer, and thus prevent crushing of the washer while the screw is being tightened and at the same time by 30 binding against the front of the drawer aid the studs 16 in preventing turning movement of both the washer and the knob. This washer is formed of steel, iron, or other cheap metal, and in order to conceal the same I employ a 35 second cover or washer 18, formed of light brass or other suitable metal and held in place by a flange at the rear end of the knob. This finished washer is also provided with an opening corresponding in shape to the boss 13, 40 and is therefore held from turning, so that none of the parts can work loose and the knob cannot become accidentally detached.

Having thus described the invention, what is claimed is—

45 1. In a securing device for furniture-fittings, a revolute threaded member provided on its inner face with projections, and a dished washer having corresponding projections on

its outer face, the inner face of said washer being provided with a plurality of wood-engaging spurs at its flanged margin, the spurs serving by engagement with the wood to prevent turning movement of the washer in 50 either direction.

2. The combination with a knob having a 55 non-circular boss, of a dished washer having peripheral wood-engaging spurs, and a boss-receiving opening at the center of the washer, one or more of the walls of said opening being turned inward to strengthen the washer, 60 and means for securing the knob in position.

3. In combination, a knob having a non-circular boss, a dished washer having a central boss-receiving opening the walls of which are turned inward for a distance corresponding 65 to the depth of the washer, integral spurs or prongs at the periphery of said washer, and means for securing the knob in position.

4. In combination, a knob having a non-circular boss; a reinforced washer having a boss-receiving opening and provided with edge 70 spurs or prongs, a finished disk covering the locking-washer and held in place by the knob, and means for securing the knob in position.

5. In combination, a knob having a non-circular boss, a locking-washer having a non-circular opening the walls of which are turned 75 inward to reinforce the washer, peripheral spurs or prongs on said washer, a washer of finished metal held in place against the locking-washer at the rear portion of the knob, a screw adapted to a threaded opening in the knob and provided with a corrugated head, and a dished washer having corrugations interlocking with those of the head, the flanged 80 peripheral portions of said dished washer having a plurality of projecting wood-engaging spurs.

In testimony that I claim the foregoing as my own I have hereto affixed my signature in 90 the presence of two witnesses.

DANIEL W. TOWER.
